ELECTRIC SWITCH

Lawrence M. Persons, Chesterfield, Mo., assignor
to McQuay-Norris Manufacturing Company,
St. Louis, Mo., a corporation of Delaware

Application August 21, 1946, Serial No. 692,104

9 Claims. (Cl. 200—144)

1

This invention relates generally to electrical control apparatus and particularly to contractors suitable for use in the power circuits of battery-operated electric trucks and the like.

The control apparatus utilized upon battery-operated electric trucks has presented a difficult problem because the electric currents being controlled are on the order of magnitude of several hundred amperes, while space is at a premium. Ordinarily, where currents of such magnitude are handled, control devices with operating and structural characteristics (e. g., great amplitude of movement, great air gaps, very large contacts, snap action, arc snuffers and blow-outs) equal to the situation can easily be provided. But, where space is at a premium, such elaborate control devices are eliminated by their intrinsic bulk. It has, for example, been found more economical to tolerate arcing at the contacts of switches utilized on electric trucks (with consequent replacement at frequent intervals) than to encumber the vehicle with apparatus which would prevent such arcing.

The object of the present invention, generally stated, is to provide a contactor compact enough for use in situations of the kind referred to, and which will require less frequent replacement of contact than heretofore.

Another object of the invention is to provide a contact arrangement which is readily reversed for equalizing contact wear and which at the same time is foolproof against reversal of polarity upon reversal of contacts.

Other objects will become apparent to those skilled in the art when the following description is read in connection with the accompanying drawings, in which:

Figure 1 is a perspective view of a contactor constructed in accordance with the present invention;

Figure 2 is a right end elevation of the contactor shown in Figure 1, part being shown in section, to reveal the relation of the parts;

Figure 3 is a sectional view taken along line 3—3 of Figure 2;

Figure 4 is a sectional view taken along line 4—4 of Figure 3 and showing the stationary contact assembly and mounting arrangement without the movable contact;

Figure 5 is a similar sectional view, but showing a modified form of stationary contact assembly and mounting arrangement therefor; and

Figure 6 is a wiring diagram showing a typical power circuit in which the control apparatus of the present invention is utilized.

In accordance with the present invention, contactors of the kind generally employed on elec-

2

tric trucks are provided with a novel arrangement of stationary and movable contacts whereby the arcing upon breaking of the power circuits is reduced and distributed so that the useful life of the contacts is prolonged. One aspect of the invention involves the provision of electrically separate though physically proximate conductors, as the movable bridge between stationary contacts. In situations where, as is common, two spaced stationary contacts, at one side of the movable contact member, are electrically connected together while like stationary contacts at the opposite side are connected in different circuits, the arcing is generally concentrated at one of the last mentioned contacts. This results from the fact that the amplitude movement of the bridge member is too limited to extinguish the arc (drawn upon separation at one of the first mentioned stationary contacts) before contact is remade through the other of the first mentioned stationary contacts. Since, as aforesaid, both of the first mentioned stationary contacts are at the same potential, arcing thereat will not continue after the very brief interval in which neither is in contact with the movable bridge. Consequently, a large arc will be drawn at the other side unless, as contemplated by this invention, the bridge member be composed of a plurality of electrically separate conductors. Such an arrangement not only equalizes the arcing between both contacts upon separation, but synergistically reduces the cumulative arc. The latter action is probably attributable, in part at least, to the fact that, upon completion of a new circuit through the bridge member which had been dead, an electromotive force is induced in the closely adjacent (though electrically separate) bridge member which has just been disengaged and is now arcing at both ends. The E. M. F. thus induced in the arcing bridge member is, however, counter to the arc-producing E. M. F. therein and consequently they tend to neutralize each other and extinguish the arc.

Another aspect of the invention has reference to the organization of the contact members so that they may not only be removed and replaced with facility but also so that pairs of the same may be readily reversed without risk of inadvertent polarity disturbance. Consequently, the invention contemplates that both the stationary and movable contact pieces be provided as permanently assembled sets, which may be reversed to equalize the wear between individual contacts of the set and yet make it impossible to connect any contact to the wrong mounting. To implement this aspect of the invention, it is contemplated that the contact sets be so arranged in cir-

cuit that the circuits are usually broken at the same set of contacts. Thereby the opposite set is saved from the destructive effects of arcing until the contact is ultimately reversed.

Referring now to the drawings for an illustrative embodiment of the invention, the apparatus is shown as an electromagnetically operated switch. The switch consists of a pair of stationary contact assemblies 1 and 2, each of which embodies two stationary contacts. The contact assembly 1 has an upper contact area 3 and a lower contact area 4, while the contact assembly 2 has an upper contact area 5 and a lower contact area 6. The areas 3 and 5 constitute one pair of contacts, and the areas 4 and 6 an opposite pair.

Arranged to bridge the stationary contact areas 3 and 5 or 4 and 6 is a movable contact assembly 7, which, as will be apparent from the drawings, bridges the odd numbered stationary contacts when in its uppermost position, but, when in its lowermost position, bridges the even numbered stationary contacts. In the embodiment shown, the movable contact assembly 7 is moved back and forth between its upper and lower positions by a suitable solenoid 8 having an axially movable core 9 biased by a spring 10 toward its upper position and arranged upon energization of the solenoid to attract the core 9 to the position shown in Figure 2. The core 9 has a stem 11 extending axially therefrom and passing through, in insulated relation to, the movable contact assembly 7. The stem 11 is provided with a shoulder 12 in order to limit movement of the movable contact assembly thereon in one direction. On the opposite side of the movable contact assembly, a spring 13 is provided and held in position by a collar 14 adjacent the end of stem 11. The spring 13 biases the movable contact assembly toward shoulder 12, but permits limited relative movement of the assembly 7 upon stem 11 against the action of spring 13. Consequently, when the solenoid is energized to move the contact assembly 7 into engagement with the lower or even numbered stationary contacts, it is contemplated that the core 9 move on for a slight degree beyond the point whereat the movable contacts have engaged the stationary contacts, so as to subject spring 13 to some compression. Contrariwise, when the solenoid 8 is deenergized, spring 10 forces the core 9 outwardly, carrying the movable contact assembly 7 into engagement with the uppermost or odd numbered stationary contacts, so that, when in this position, the contacts are urged together under the tension of spring 10. Consequently, in both contact-making positions, the movable contact is spring-pressed into engagement with the stationary contacts.

As hereinbefore mentioned, the invention is characterized by the organization of the movable contact assembly 7, so as to provide a pair of parallel conductors 15 and 16, separated one from the other by a layer of insulation 17, whose thickness is such as to reduce the physical spacing between conductors 15 and 16 substantially to the minimum consistent with adequate dielectric to electrically insulate the conductors 15 and 16 one from the other. The conductors 15 and 16 are mechanically secured together by studs of insulating material 18 and also held in mechanical assembly by the arrangement of insulation sleeve 19 and insulating washers 20 and 21, as clearly shown in Figure 3.

At each end of each of the conductors 15 and 16, a layer of contact material 22 is suitably af-

fixed in accordance with the usual practice, thereby providing two pairs of contact areas, one pair of conductor 15 and the other pair on conductor 16. In view of the magnitude of currents required to be handled by such a device, the conductor elements 15 and 16 are substantially heavy and rigid, having a cross sectional area adequate to conduct currents on the magnitude of several hundred amperes.

Another aspect of the invention concerns the organization of the stationary contact assembly, as shown more in detail in Figure 4. The stationary contact assembly 1 consists of a pair of identical bars 22 and 23. Like the conductors 15 and 16, the bars 22 and 23 are relatively heavy and rigid and are bent so as to provide a central spaced portion of greater separation than at their ends. At the central portion of each of bars 22 and 23, contact members 3 and 4 of suitable contact material are affixed.

The bar 22 has a large hole 24 at one end and a small hole 25 at the other end. Likewise, the bar 23 has a large hole 26 at one end and a small hole 27 at the other end, it being noted that the bars 22 and 23 are identical, but in reversed relation in the assembly. The ends of the bars 22 and 23 are separated at each end by an insulation spacer 28. Within the large hole 24 of bar 22 and large hole 26 of bar 23, an insulation sleeve 29 is placed. Within the insulation sleeve 29 a headed connector 30 extends and is electrically and mechanically joined at 31 to the bar through whose small hole (25 or 27) it extends. The headed portion of each connector 30 is electrically insulated from its adjacent bar (22 or 23) by an insulating washer 32, but provides a contact head. The assembly just described consists throughout of duplicated parts, which, however, are arranged in diametrically symmetrical relation so that the assembly may be turned end-for-end to bring the parts formerly at one end into the precise position formerly occupied by the parts at the other end.

The contact assembly just described is mounted upon a pair of mounting posts 33 and 34, which extend through an insulating panel 35 and are therebelow connected to the appropriate electrical circuits. Each of the mounting posts 33 and 34 is provided with a seat for the reception of the contact assembly, but these seats differ in elevation, as shown at 36 and 31. Consequently, if the contact assembly be removed from the posts 33 and 34, turned about its longitudinal axis, and replaced upon the mounting posts, it will not fit the seats. Obviously, if such reversal about the longitudinal axis were made, it would result in the upper contact (which is intended to be electrically connected through post 33) being in electrical connection with post 34 and the same reversal would prevail with respect to the lower contact. With the arrangement shown, however, the assembly may be reversed end-for-end without disturbing the fitting relation of the contact assembly upon the seats 36 and 31 and without disturbing the electrical relation between the upper and lower contacts and the corresponding mounting posts 33 and 34. In an apparatus of the kind referred to, severe arcing takes place at some contacts, but not at others, and consequently it is highly desirable to be able to reverse the relation of contacts (without reversing their polar orientation) in order to equalize the wear and erosion upon the contacts. It is further desirable to provide an arrangement which, while permitting

such reversal of contacts, will not permit reversal of their polar orientation because, in practice, such reversal of contacts is frequently required to be made by workmen who are electrically unskilled.

A modified form of reversible contact assembly is shown in Figure 5. In this embodiment, the assembly may be reversed either end-for-end or about a longitudinal axis without changing the polar orientation of the contacts. In this form, two identical contact bars 122 and 123 are provided with a countersunk hole 124 at each end thereof. The bars 122 and 123 are mechanically connected by an insulation sleeve 125, which spaces the bars 122 and 123 and mechanically connects the same by being peened or molded into the countersunk holes 124, as shown. Mounting post 33 is provided with a seat 136 of conducting material, while mounting post 34 is provided with a seat 137 of insulating material, but being otherwise identical to seat 136. In order to assure against reversal of polar orientation of the contacts with reference to the mounting posts upon reversal of the contact assembly, the upper end of post 33 is provided with a connecting means which is not interchangeable with the connecting means at the top of post 34. In the embodiment shown, the upper end of post 33 is provided with a threaded portion 133 of lesser diameter than the threaded portion 134 of post 34. A nut 135 of conducting material is provided for post 34, while a nut 132 of insulating material is provided for post 33. The nut 132 may, if desired, be made of metallic substance if care be exercised that an insulating washer, such as 131, be at all times interposed between the nut 132 and bar 122. While this form of contact assembly is less foolproof than the form illustrated in Figure 4 in that the insertion of a metallic washer at 131 will defeat the purpose of the arrangement, it nonetheless has the virtue that it may be reversed about either axis.

In the wiring diagram shown in Figure 6, four contactors of the character hereinbefore described are utilized, as indicated at 72, 70, 71, and 73. The contactors are provided with operating solenoids 82, 80, 81, and 83, respectively, as shown. The control circuit for the solenoids just mentioned is not shown, but it will be apparent from Figure 6 that, when contactor 70 is moved to its lowermost position, a starting circuit is established from the battery 40 through the lower contacts of contactor 70, field 41, the upper contacts of contactor 71, the upper contacts of contactor 72, resistor 42, resistor 43, and the armature of motor 44. When contactor 72 is actuated to close its lowermost contacts, a second speed circuit is established, as before, to contactor 72, but therefrom shunted about resistor 42. Upon the movement of contactor 73 to its lower position (the other contactors remaining in their previously described positions), a third speed circuit is established by throwing the resistors 42 and 43 into parallel. If now, while contactor 72 remains in its lower position, solenoid 82 be deenergized so as to permit contactor 72 under the influence of its spring 10 to move to its upper contact-making position, both of resistors 42 and 43 will be shunted out of the circuit and a fourth speed established.

Contactor 71, when moved to its lower contact-closing position, establishes the circuit for reverse operation, it being understood in this connection that the control circuits for solenoids 80

and 81 are so interlocked that contactor 70 must be in its upper position before contactor 71 can be moved to its lower position and vice versa. Thereby the forward and reverse running circuits are both made and broken at the lower contacts of the contactors and no arcing takes place at the upper contacts thereof.

In order to illustrate the arc-reducing characteristic of contactors having movable contact members constructed in accordance with the present invention, the action of contactor 72 may be considered. When, with the motor operating on starting circuit, contactor 72 is separated from its upper contacts, an arc will be drawn at each end thereof. Momentarily, after such separation, however, contact is made between the lower contacts of contactor 72. The circuit thus established through the lower conductor of contactor 72 is parallel with, and in the same direction as, the current flowing through the arcs at the upper conductor of contactor 72. The magnetic field, which is thrown out as the current in the lower conductor of the contactor builds up to the high magnitude involved in situations of this type, induces an electromotive force in the arcing upper conductor. Such induced electromotive force is, according to Lenz law, counter to the direction of the impressed electromotive force which is causing the arcs. In order to tend to extinguish the arc lingering at the just-broken contacts, it is necessary that the current traversing the just-engaged contacts be of a high order of magnitude and that the upper and lower conductors of the movable contact be so physically proximate that the current building up in one will induce a substantial counter E. M. F. in the other.

From the foregoing description, those skilled in the art should understand the operation and advantages of the present invention and realize that, while one complete example has been disclosed in full, the invention is not limited to the details of the example, but is susceptible of many modifications without departing from the spirit thereof or the scope of the appended claims.

Having thus described the invention, what is claimed and desired to be secured by Letters Patent is:

1. In combination with a switch having a pair of stationary contact assemblies, each assembly having an upper and a lower contact insulated from each other, a movable contact member, said movable contact member having two insulated conducting bridges each having a contact at each end thereof, the contacts on one bridge arranged to engage the upper contacts of both stationary contact assemblies and the contacts on the other bridge arranged to engage the lower contacts of both stationary contact assemblies, said contact assemblies being identical and symmetrical, and means at each end for mounting the assemblies for reversibility without change of polarity, said mounting means being structurally different at the respective ends.
2. In a switch having stationary contacts and a movable contact member whose amplitude of movement is limited to less than sufficient to provide a contact separation of a magnitude such as to provide an air gap across which heavy currents will not maintain an arc upon separation of the contacts, said movable contact member having two pairs of contact areas, one pair of which engage their corresponding stationary contacts only when said member is at one extreme of its movement and the other pair of con-

tact areas engage their corresponding stationary contacts only when said member is at the opposite extreme of its movement, one of the stationary contacts in each of the pairs thereof being permanently electrically connected to one contact of the other pair, the movable contact areas of each pair being electrically and mechanically connected together and mechanically connected with but electrically insulated from the contact areas of the other pair; each of the 10 said stationary contacts of one pair being permanently assembled with one of the stationary contacts of the other pair so that only one contact of an assembly is engageable by the movable contact member at one time; each of said assemblies including identical connectors at opposite ends of the contacts, one of said connectors being electrically connected to one contact and insulated from the other and another connector being reversely connected to the contacts whereby the assemblies are diagonally symmetrical, and mounting posts arranged to releasably retain the assemblies in operative position.

3. A contact assembly comprising a pair of identical contact elements, a pair of identical connectors, and a pair of identical insulators, one of the connectors electrically engaging one contact member and insulated from the other contact member by one of the insulators, and the other of the connectors electrically engaging the other of the contact members and insulated from the first contact member by the other one of the pair of insulators, said parts being secured together with the members of each pair in reverse orientation whereby the assembly is diagonally symmetrical but transversely unsymmetrical.

4. A contact assembly comprising an upper contact bar, a lower contact bar identical with the upper contact bar, means for permanently associating said bars together, a pair of connectors releasably engaging said bars at opposite ends thereof, one of said connectors being electrically and mechanically connected to the upper contact bar and mechanically connected to but electrically insulated from the lower contact bar, and the other of said connectors being mechanically and electrically connected to the lower contact bar and mechanically connected to but electrically insulated from the upper contact bar.

5. A contact assembly comprising an upper contact bar, a lower contact bar identical with the upper contact bar, a connector electrically and mechanically connected to the upper contact bar and mechanically connected to but electrically insulated from the lower contact bar, and another connector mechanically and electrically connected to the lower contact bar and mechanically connected to but electrically insulated from the upper contact bar, said connectors each having a contact head overlying its mechanical connection to the contact bar from which it is electrically insulated.

6. The combination with a contact assembly having upper and lower contact elements permanently mechanically connected together but insulated one from the other, of a pair of mounting posts for removably and reversibly receiving said contact elements, each of said posts passing through both contact elements, one of said mounting posts being insulated from the upper contact element and the other from the lower.

7. In combination with a contact assembly having upper and lower contact elements permanently mechanically connected together but

insulated one from the other, a pair of mounting posts for reversibly receiving said contact elements, each of said posts passing through both contact elements, one of said mounting posts being insulated from the upper contact element and the other from the lower, and structurally dissimilar means at each mounting post for interfering with the interfit between said contact assembly and the mounting posts when the electrical relation therebetween is improper.

8. In combination in a contactor having a contact carrier movable between two positions whereat contact is made between different pairs of stationary contacts respectively, a conducting bridge on said carrier comprising two electrically separate conductors, one for engagement with each of the pairs of stationary contacts, said stationary contacts (in different pairs) at one end of the bridge being electrically connected together, and said conductors being assembled together with an intervening layer of insulation, said layer of insulation being contiguous with both conductors and of such thinness that the inductive effect in one conductor of increasing current in the other conductor is such as to extinguish arcs drawn at said one conductor when said bridge is moved into position whereat said other conductor engages its stationary contacts.

9. In a contactor having a bridge movable between two positions at each of which one electrical circuit is made and another broken, a pair of stationary contacts arranged to be engaged by the bridge when in one of its positions, a second pair of stationary contacts arranged to be engaged by the bridge when in the other of its positions, the respective contacts of each pair being disposed for engagement with opposite ends of the bridge, said bridge comprising two parallel conductors, one of which engages the first mentioned pair of stationary contacts, and the other of which engages the second pair of stationary contacts, said conductors being physically proximate but electrically separated from each other at least at one end and along the portion which extends between the individual contacts of the respective pairs, and means for maintaining the stationary contacts (in different pairs) at the end of said conductors opposite said one end at the same electrical polarity irrespective of the position of the bridge, whereby the increasing current in a conductor just engaged with its contacts induces in the other conductor just separated from its contacts an electromotive force opposite in direction to that to which said other conductor has been subject, so that the amplitude of movement of said bridge between its said two positions may be less than the air gap required to extinguish an arc drawn upon separation of said bridge and a stationary contact.
